Valve Company, Milwaukee, Wis., a corpora-
tion of Wisconsin

Application May 9, 1941, Serial No. 392,644

4 Claims. (Cl. 4—288)

The present invention relates generally to improvements in plumbing fixtures, and relates more specifically to improvements in the construction and operation of devices for removing debris from the liquid delivered from a wash basin, sink or the like.

An object of the invention is to provide an improved strainer for sinks or the like, which is simple and durable in construction, which may be conveniently and effectively applied to a sink or wash basin, and which is moreover highly efficient in use.

Perhaps the most popular sink strainer now in use for the purpose of removing debris such as garbage from the liquid which is drained from kitchen sinks or the like, is the type shown in Judell Patent 1,811,852, granted June 30, 1931. This strainer comprises in general, a cup-shaped cast-metal main casing adapted to be suspended through a hole in the sink bottom by means of a relatively wide integral peripheral external flange at the upper casing end, a strainer basket constructed of sheet metal and formed for removable suspension within the fixed main casing, and a stop plug adjustably supported from the bottom of the basket and being cooperable with a central opening in the lower portion of the main casing to control the delivery of liquid from the sink basin. In order to clamp the main casing to the sink, it has heretofore been customary to cause the integral upper casing flange to directly engage an upper surface of the sink bottom, and to provide a clamping ring cooperable through a gasket with a lower surface of the sink and coacting with external screw threads on the cast casing. The relatively wide upper surface of the integral casing flange was therefore exposed to view at all times, and it was necessary to heavily plate this constantly exposed surface of the flange to correspond with the finish of the strainer basket and of the other sink fixtures. Due to the frequent normal use of scouring powder and the like, it required extremely heavy plating of these upper exposed flange surfaces, and while the external lower surfaces of the main casing were never exposed and the other internal and upper surfaces were seldom exposed to view for any great length of time, it was necessary in order to facilitate the plating operation, to plate and finish a considerable portion of the entire outer surface of the cast casing at relatively great expense, thus also wasting plating stock. The strainer baskets can be formed of stainless steel in order to avoid plating, but the main casing is preferably con-

structed of cast metal due to the application of screw threads thereto and must therefore be plated, and since these castings are relatively thin, the integral suspension flanges are also rather thin and frail, and sometimes break when the clamping pressure is applied. For these reasons considerable difficulty was heretofore encountered with the prior sink strainer assemblages of this particular and most popular type. It is therefore a more specific object of our present invention to provide improved suspension means for the main casings of these basket type sink strainers, whereby all of the above mentioned difficulties are eliminated, and which can be manufactured and sold at moderate cost without inferior appearance.

Another specific object of this invention is to provide a new and useful attachment for firmly securing a sink strainer or the like to a wash basin, in a neat and expeditious manner and without danger of breaking or otherwise damaging the basin or the fastening elements.

A further specific object of the present invention is to provide an improved clamping assemblage for rigidly suspending a strainer casing from the bottom of a kitchen sink or the like, which can be constructed of sheet metal and at minimum cost, and which will present a neat and highly finished appearance at all times.

Still another specific object of our invention is to provide an improved mode of producing durable and highly finished clamping rings for the main casings of basket type sink strainers, from the same stock used in the formation of the baskets and without wasting materials.

An additional specific object of the invention is to provide an improved sheet metal clamping ring for fastening a strainer assemblage to its supporting structure, without danger of damaging the enamel or other coating on the structure.

These and other objects and advantages of the present invention will be apparent from the following detailed description.

A clear conception of an embodiment of our invention, and of the mode of producing the improved sink strainer assemblages, may be had by referring to the drawing accompanying and forming a part of this specification wherein like reference characters designate the same or similar parts in the various views.

Fig. 1 is a top view of one of our improved basket type sink strainer assemblages, portions thereof having been broken away in order to reveal lower parts;

Fig. 2 is a central vertical section through a

partially assembled perspective view of the strainer unit; and

Fig. 3 is a central vertical section through the fully assembled unit, showing the same attached to a fragment of its normal support.

While the invention has been shown and described herein as being specifically embodied in a basket type kitchen sink strainer assemblage having a cast metal main casing and a sheet metal basket detachably cooperable therewith, it is not our desire or intent to thereby unnecessarily restrict the scope or the utility of the improvement.

Referring to the drawing, the improved sink strainer unit shown therein, comprises in general, a main annular cast-metal cup-shaped casing 6 having an upper outwardly extending peripheral rim 7, and a lower central liquid discharge duct 8 provided with an annular tapered plug seat 9 at its upper end; a cup-shaped sheet-metal strainer basket 10 provided with a multiplicity of perforations 11 and having an upper outwardly directed peripheral flange 12 adapted to rest upon the upper extremity of the main casing 6, while its lower central portion is provided with a fixed hub 13 having a bore formed with slots 14 extending therealong; a disk-like stopper plug 15 formed for sealing coaction with the seat 9, and being vertically adjustably suspended from the lower end of an upright stem 16, the upper end of which has a manipulating knob 17 and the medial portion of which is provided with radial suspension lugs 18 movable along the slots 14 and adapted to coact with the top of the hub 13 when the elevated stem 16 is rotated; an annular sheet-metal main casing suspension flange or ring 19 having an inner depressed edge 20 formed to receive the casing rim 7, and also having a relatively wide approximately plane outer portion adapted to rest upon an upper surface of the basin bottom 21; and a clamping ring 22 adjustable along screw threads 23 formed on the main casing 6 directly beneath the rim 7, and normally coacting through a gasket 24 and a pliable sealing washer 25 with the lower surface of the sink bottom 21.

The main cast-metal casing 6 is of relatively thin formation throughout, and the upper enlarged part of this casing provides a cup-like space within which the basket 10 is adapted to be vertically removably and centrally suspended with the aid of the basket flange 12, so that the sides and bottom of the basket will not contact the casing interior. The exterior of the lower extremity of the casing 6, surrounding the discharge duct 8, is provided with other screw threads 26 adapted for coaction with a coupling ring 27 associated with a drain pipe 28, and the delivery end of the duct 8 is ordinarily provided with a perforated secondary strainer plate 29, as shown in Fig. 3. Since the main casing is normally totally concealed, it need not be highly finished.

Both the strainer basket 10 and the casing suspension ring 19 may be formed of sheet-metal of the same gauge, and in order to avoid necessity of plating, these elements may be produced from stainless-steel or other non-corrosive metal capable of taking a polish. The basket 10 and ring 19 may be constructed with the aid of punches and dies, and in accordance with one feature of our invention, both of these elements may be formed from the same sheet of metal by utilizing the stock which surrounds the blank from which the basket 10 is made, to form the blank for the 75

suspension ring 19. In this manner waste of stock will be minimized, and the cost of production of the sheet metal elements will be reduced to a minimum.

- 5 The internally bored and slotted hub 13 may be rigidly secured centrally within the basket 10 in any suitable manner, and the stopper 15 which is adapted to coact with the annular seat 9 may be formed of cast metal and secured to the lower 10 end of the stem 16 in any suitable manner, as by riveting. The top of manipulating knob 17 which is secured to the upper end of the stem 16, 15 preferably lies flush with or beneath the plane of the top of the basket 10 when the stop plug 15 is elevated as in Figs. 2 and 3; and the retainer lugs 18 on the stem 16 are adapted to either rest upon the upper end of the hub 13, or they may be slid downwardly through the slots 14 to thereby permit seating of the plug against the casing seat 9.
- 20 The knob 17 besides serving as means for manipulating the stopper plug 15, also serves to effect bodily removal of the basket 10 from the main casing 6, and the latter is permanently attached to the sink.
- 25 The sheet metal clamping flange or ring 19 is relatively thin and flexible, and the inner depressed edge 20 of this ring should be formed for snug coaction with the casing ridge or rim 7, and to permit the uppermost end of the main 30 casing 6 to lie slightly below the plane of the upper surface of the sink bottom 21. The upper surface of the flange ring 19 should lie approximately flush with the upper surface of the basin bottom 21 when clamping has been effected, and 35 when the clamping ring 22 is finally adjusted upwardly along the casing threads 23 to force the pliable sealing ring into snug coaction with the lower surface of the sink bottom 21 as in Fig. 3, the flange ring 19 may deflect slightly and will 40 thus snugly engage the opposite upper surface of the bottom 21.

When the various parts of the improved strainer assemblage have been properly constructed as above described, it is a simple matter to attach the unit to a sink or other basin having a receiving opening in the bottom 21 thereof. Upon removal of the clamping ring 22, gasket 24 and washer 25, the casing 6 with the flange ring 19 applied thereto, may be dropped through the 45 receiving opening in the sink bottom 21, whereupon the washer 25, gasket 24, and clamping ring 50 22 may be applied about the casing 6 as shown in Fig. 3. When the clamping ring 22 is finally driven home, a liquid tight joint will be produced 55 between the sink and strainer, by the flange ring 19 and pliable sealing washer 25. The drain pipe 28 may be subsequently connected to the casing 6 with the aid of the coupling ring 27 whereupon the assemblage is ready for normal use. Such use will be obvious from the foregoing detailed description.

From the above specific description it will be apparent that our present invention provides simple, durable and efficient means for firmly suspending a strainer casing 6 or the like, from an enamelled sink bottom or a similar support, without danger of damaging the enamel or other coating. The improved suspension means also provides a neat and effective sealed joint, and eliminates necessity of plating or otherwise finishing the cast-metal casing. The suspension flange or ring 19 may be finished in any desired manner at moderate cost, and can be produced from the same stock which is used in the formation of the basket 10, in order to reduce the cost

and to eliminate waste of this stock. The use of sheet metal in the formation of the suspension ring 19, besides providing a flexible suspension flange, eliminates objectionable breakage of these flanges as when formed integral with the casing 6, since the sheet metal flange ring 19 is formed separate from the main casing. By forming the ring 19 and basket 10 of non-corrosive sheet metal, expensive plating and finishing of these parts may be avoided, and the cost of manufacture of the strainer units is thereby minimized. The improved assemblages may be readily manufactured and installed by a novice, and are highly efficient and successful in actual use.

It should be understood that it is not desired to limit this invention to the exact details of construction, or to the precise mode of use, herein shown and described, for various modifications within the scope of the appended claims may occur to persons skilled in the art.

We claim:

1. In combination with a basin having a bottom provided with an opening and an annular recess disposed between the periphery of said opening and the adjacent upper surface of said bottom, a rigid cup-shaped casing having an integral upper outwardly projecting peripheral rim disposed within said opening beneath said recess, a relatively flexible suspension flange seated within said recess with its top surface approximately flush with said upper basin surface and having an integral inner portion extending downwardly between said opening and the periphery of said casing rim and projecting inwardly beneath the latter, and a clamping ring screw threaded for adjustment along the outer portion of said casing to force said flange within said recess and said casing rim against said inwardly directed lowermost flange portion.

2. In combination with a basin having a bottom provided with an opening and an annular recess disposed between the periphery of said opening and the adjacent upper surface of said bottom, a rigid cup-shaped casing having an integral upper outwardly projecting peripheral rim disposed within said opening beneath said recess, a relatively flexible suspension flange seated within said recess with its top surface approximately flush with said upper basin surface and having an integral inner portion extending downwardly between said opening and the periphery of said casing rim and projecting inwardly beneath the latter, a clamping ring screw threaded for adjustment along the outer portion of said casing to force said flange within said recess and said casing rim against said inwardly directed lowermost flange portion, and a cup-shaped element adapted for disposition within said casing and having an outwardly

directed upper flange resting upon the top of said casing rim with its uppermost portion approximately flush with the top surface of said flexible suspension flange.

5. 3. In combination with a basin having a bottom provided with an opening and an annular recess disposed between the periphery of said opening and the adjacent upper surface of said bottom, a rigid cup-shaped casing having an integral upper outwardly projecting peripheral rim disposed within said opening beneath said recess, a relatively flexible annular suspension flange seated within and substantially filling said recess and with its top surface approximately flush with said upper basin surface, said flange having an integral annular inner portion extending downwardly between said opening and the periphery of said casing rim and also having an integral annular inward projection at the lower end of said downwardly extending portion snugly embracing the adjacent wall of said casing and coacting with the bottom of said rim, and a clamping ring screw threaded for adjustment along the outer lower portion of said casing to simultaneously force said flange downwardly into said recess and said casing rim against said inward projection of said flange.
10. 4. In combination with a basin having a bottom provided with an opening and an annular recess disposed between the periphery of said opening and the adjacent upper surface of said bottom, a rigid cup-shaped casing having an integral upper outwardly projecting peripheral rim disposed within said opening beneath said recess, a relatively flexible annular suspension flange seated within and substantially filling said recess and with its top surface approximately flush with said upper basin surface, said flange having an integral annular inner portion extending downwardly between said opening and the periphery of said casing rim and also having an integral annular inward projection at the lower end of said downwardly extending portion snugly embracing the adjacent wall of said casing and coacting with the bottom of said rim, a clamping ring screw threaded for adjustment along the outer lower portion of said casing to simultaneously force said flange downwardly into said recess and said casing rim against said inward projection of said flange, and a cup-shaped element adapted for disposition within said casing and having an outwardly directed upper annular flange resting upon the top of said casing rim within said inner annular portion and with its uppermost portion approximately flush with the top surface of said flexible suspension flange.
